ATTORNEY.

UNITED STATES PATENT OFFICE.

WILLIAM C. WINFIELD, OF WARREN, OHIO, ASSIGNOR TO THE WINFIELD
MANUFACTURING COMPANY, OF SAME PLACE.

DESIGN FOR A CAN.

SPECIFICATION forming part of Design No. 22,517, dated June 6, 1893.

Application filed April 29, 1893. Serial No. 472,436. Term of patent 7 years.

to all whom it may concern:

Be it known that I, WILLIAM C. WINFIELD, a citizen of the United States, and a resident of Warren, in the county of Trumbull and State of Ohio, have invented and produced a new and original Design for Cans, of which the following is a full, clear, and exact description, reference being had to the drawing, making part of this specification.

10 A single perspective view of the can serves to illustrate the design.

—A— represents the body of the can which embodies my new design. This has a top which is distinguished largely by tri-circles or rings —a—, —b— and —c—, standing out 15 in clearly defined elevations from the substantially flat surfaces —d— and —e—, which are displayed between said circles or rings.

Within the ring —c— is the large central depression which takes in the middle of the top 20 and has a flat surface —C— bordered by a vertical wall —h—, terminating in the circle or ring —c—. Two openings —m— and —n— are shown in the surface —C—, one larger than the other, and a dish shaped cover —D—, 25 is in raised position so as to reveal the appearance of the entire top.

Having thus described my invention, what I claim as new, and desire to secure by Letters Patent, is—

30 The design for a can as described and shown.

WILLIAM C. WINFIELD.
